James Andrews.

Andrews and Dixon designs - Design for Parlor grate

Patented Sept. 11, 1855

FIG. 1

FIG. 2.

Des. 728

James Andrews of Philadelphia Pa. Assignor to
Andrews & Dixon of Philadelphia aforesaid
Letter Patent No 728. - Dated Sept 11th 1855.

The schedule referred to in this Letter Patent and making part of the same -

My invention consists in a new design for parlor grates the same being
represented in the accompanying drawings in which,

Fig 1. is a front view of the grate.

Fig 2. a vertical middle section from front to rear.

Fig 3. a middle cross section through the hearth and fender (detached)

The fire chamber a. is dome shaped. The fire brick rises in a curve
from front to rear and is capped with a suitable molding. c.

The grate d. is what is called a "lowdown grate" and the extension of
the hearth e. is provided with a suitable fender m. The arch n. and tablet o. complete the
design.

What I claim as my invention is the design for parlor grates as
above set forth,
